(57) **CLAIM**

The ornamental design for a carrying case with backbone, as shown and described.

DESCRIPTION

FIG. 1 is a right-front perspective view of a first embodiment of a carrying case with backbone;

FIG. 2 is a right-rear perspective of the carrying case according to FIG. 1;

FIG. 3 is a right side view of the carrying case according to FIG. 1;

FIG. 4 is a left side view of the carrying case according to FIG. 1;

FIG. 5 is a front view of the carrying case according to FIG. 1;

FIG. 6 is a rear view of the carrying case according to FIG. 1;

FIG. 7 is a top view of the carrying case according to FIG. 1;

FIG. 8 is a bottom view of the carrying case according to FIG. 1;

FIG. 9 is a right-front perspective view of a second embodiment of a carrying case with backbone;

FIG. 10 is a right-rear perspective of the carrying case according to FIG. 9;

FIG. 11 is a right side view of the carrying case according to FIG. 9;

FIG. 12 is a left side view of the carrying case according to FIG. 9;

FIG. 13 is a front view of the carrying case according to FIG. 9;

FIG. 14 is a rear view of the carrying case according to FIG. 9;

FIG. 15 is a top view of the carrying case according to FIG. 9; and,

FIG. 16 is a bottom view of the carrying case according to FIG. 9.
